DRIP CATCHING ATTACHMENT FOR UMBRELLAS

Filed June 13, 1938

INVENTOR.
BY Clarence D. DeLamater
A. B. Bowman
ATTORNEY.

a substantially frusto-conical hollow member, and a hollow cylindrical stem gripping portion extending in the hollow portion in alignment with the axis of said frusto-conical member.

- 5 3. In a drip catching attachment for umbrellas or the like, a hollow resilient body member, means

for securing it to an umbrella top, said means including a resilient hollow cylindrical portion positioned centrally within said hollow, resilient body member.

CLARENCE D. DE LAMATER. 5
